UNITED STATES PATENT OFFICE.

ALEXANDER F. JENKINS, OF BALTIMORE, MARYLAND.

ACETYLENE-GENERATING SYSTEM.

1,096,248.

Specification of Letters Patent. Patented May 12, 1914.

Continuation of application Serial No. 640,064, filed July 24, 1911. This application filed August 7, 1912. Serial No. 713,821.

To all whom it may concern:

Be it known that I, ALEXANDER F. JENKINS, a subject of the King of Great Britain, residing at Baltimore city, State of Maryland, have invented certain new and useful Improvements in Acetylene-Generating Systems, of which the following is a specification.

This invention relates to improvements in acetylene generators of that type in which a suitable vapor, such as steam, acts upon the calcium carbid to produce acetylene gas for lighting or any other purposes, the generator being especially useful for train, car, vessel and house lighting systems where a heating fluid, such as steam, or products of combustion, or electricity, may be utilized to produce vapor within the acetylene generator. In carrying out the invention, a vapor producing device is arranged within the carbid holding compartment of the generator and water or other liquid in small quantity is supplied to the vapor producer so that the heat will vaporize the water, the feed of the water being automatically governed by the pressure of the generating gas acting on a controlling valve. The heating medium may be steam taken from the train pipe of a railroad car, from the boiler of a house heating system or steam propelled vehicle, or it may be the products of combustion from a furnace or internal combustion engine, such steam or products of combustion being conveyed through a pipe or conduit which vaporizes the water fed to the acetylene generator. Furthermore, the heat for vaporizing the water may be derived from an electric resistance element suitably supplied with current, an electric thermal vapor producer of this character being especially adaptable for electrically propelled street and interurban cars equipped with a lighting system using acetylene gas. An acetylene generator equipped with the electric vapor producer is advantageous in a portable oxyacetylene metallurgical outfit since a current can be supplied to the set from any available source through a cable.

In the accompanying drawing, which illustrates certain embodiments of the invention, Figure 1 is a side view of the generator with portions in section to show the fluid thermal vapor producer. Fig. 2 is a vertical transverse section of the generator. Fig. 3 is an enlarged detail view of a pressure con-

trol water supply valve, in combination with an electric thermal vapor producer.

Similar reference characters are employed to designate corresponding parts throughout the views.

Referring to the drawing, A designates a casing of suitable form, such for instance, as a metal cylinder having heads 1 and 2 at opposite ends, the former being readily removable so as to permit access to the generating chamber 3 in which is a carbid holding basket 4 and an ash-receiving tray 5, the basket resting on horizontal ledges 6 secured at opposite sides within the cylinder A. The end of the cylinder opposite from the generating chamber 3 forms a washer chamber 7 through which the gas passes before being consumed. In order to keep the washer cool, an air cooling chamber 8 formed by transverse partitions 9 and 10 may be provided and air may freely circulate through this chamber by means of openings or passages 11. From the chamber 3, the gas is conducted through a pipe 12 to the bottom of the washer chamber and therein the gas rises through the body of water and is discharged through the outlet pipe 13 that connects with a lighting system, oxyacetylene burner or the like.

The acetylene gas is produced by vapor acting on the carbid in the basket 4, and for producing this vapor a vaporizer 14 is arranged in the chamber 3 above the basket 4, the vaporizer being a body of suitable material that will hold the water dropped thereon and allow it to be converted into vapor. The water is supplied through a valve mechanism B which is mounted on the cylinder A directly over the vaporizer and this valve mechanism B comprises a casing 15 which is in open communication with the generating chamber 3 through a port or opening 16, and the water admitted through the valve device B passes through the port 16 and the vaporizer 14. In one wall of the casing 15 is a resilient diaphragm 17 that has connected therewith a rod 18 which terminates in a valve 19 adapted to open and close a passage 20 leading from the inlet chamber 21 to the interior of the casing 15. Behind the diaphragm 17 is a spring 22 which is capable of adjustment by a screw 23 so that any desired tension can be placed on the diaphragm. The pressure of the generated gas acts outwardly on the diaphragm and tends to move the rod 18 and thereby open the valve 19.

to close the valve 19 in opposition to the spring 22, and hence by properly adjusting the spring the valve will open and close in such a manner as to maintain a substantially 5 uniform gas pressure in the generator. By means of this valve device, the pressure of the gas may be readily adjusted for different classes of service, such as lighting, oxyacetylene welding or metal welding or cutting, or 10 charging of tanks with the acetylene gas under high pressure directly and without the use of pumping apparatus. The water or other liquid to be converted into vapor or steam is supplied to the inlet chamber 21 15 through a pipe 24. The heating of the vaporizer or steam generator 14 may be accomplished by the use of steam, products of combustion, or electric current.

In Fig. 1, a steam pipe 25 is shown which 20 has a portion 26 disposed within the generating chamber 3 and in heat-conducting contact with the body 14 of the vaporizer so as to heat the latter to such a temperature as to cause the water to vaporize. The pipe 25 25 may be a branch from a train steam pipe, or it may be a separate pipe connected with a locomotive where acetylene head-lighting is desired, or it may be a branch of a house heating system, or it may be a conduit 30 through which products of combustion pass, as where the generator is used for lighting purposes in connection with automobiles, motor boats or other vehicles driven by an explosive engine.

35 In Fig. 3, the vaporizer is heated by an electric resistance element 27 which may be connected with a suitable source of current by leading-in wires 28 and 29. In either form of the device, should the lighting 40 medium become deranged or interrupted for any reason, the generation of the gas is not interfered with because the water supplied to the vaporizer, instead of being vaporized, will drop directly on the carbid and cause 45 gas to be generated so that the lights supplied by the generator will continue to burn. This is an important feature when the generator is used in connection with train lighting or vehicle lighting where it often happens 50 that the cars are disconnected from the locomotive which is the source of the heating element, or the engine of the vehicle is stopped while it is necessary to keep the lights burning.

55 From the foregoing description, taken in connection with the accompanying drawings, the advantages of the construction and of the method of operation will be readily apparent to those skilled in the art to which 60 the invention appertains, and while I have described the principle of operation of the invention, together with the apparatus which I now consider to be the best embodiment thereof, I desire to have it understood 65 that the apparatus shown is merely illustra-

tive, and that such changes may be made when desired as are within the scope of the claims appended hereto.

Having thus described the invention, what I claim as new is:—

70 1. The combination of an acetylene generator including means for holding carbid, a vaporizer for generating vapor to act on the carbid, means for heating the vaporizer, and means controlled by the pressure of the generated gas for directing liquid upon the vaporizer to produce vapor in such quantity as to maintain a substantially uniform gas pressure.

80 2. The combination of an acetylene generator including means for holding carbid, with a flameless thermal vapor producing means within the generator for generating acetylene gas by the action of the vapor on the carbid.

85 3. The combination of an acetylene generator including means for holding carbid, a vaporizer in the generator, means for heating the vaporizer, means for supplying liquid to the vaporizer to produce vapor, and an automatically actuated valve controlled by the pressure of the generated gas for governing the supply of water delivered to the vaporizer.

90 4. The combination of an acetylene generator including means for holding carbid, a flameless vaporizer disposed in proximity to the said means, means for heating the vaporizer, and means for supplying water to the vaporizer to produce vapor when the 100 vaporizer is heated and to drip from the vaporizer upon the carbid to generate gas when the vaporizer is unheated.

95 5. The combination of an acetylene generator including means for holding carbid, 105 means for supplying liquid to the carbid, and means within the body of the generator capable of converting the liquid to vapor before reaching the carbid whereby gas can be generated by the liquid direct or by the 110 vapor.

6. The combination of an acetylene generator including a carbid holder, a conduit for a heating medium, a vapor generator heated thereby for supplying vapor to act 115 on the carbid, and an automatically controlled valve for supplying liquid in such quantity to the vaporizer as to produce vapor to generate gas in accordance with the demand.

120 7. The combination of an acetylene generator including a carbid holder, a conduit extending through the generator for a heating medium, means for supplying liquid to produce vapor by the heat from the said medium.

8. The combination of an acetylene generator including a carbid holder, a conduit disposed above the holder and adapted to receive a heating medium, means above the 130

- conduit for supplying water for generating vapor by the heating medium and for permitting water to drop upon the carbid when the heat is not sufficient to generate vapor, 5 and a valve responsive to the pressure of the generated gas for controlling the supply of water.
9. The combination of an acetylene generator including a carbid holder, an electro thermal vaporizer in the generator, and means responsive to the pressure of the generated gas for delivering water upon the vaporizer to generate vapor in the presence of the carbid.
- 15 10. The combination of a gas-holding receptacle, means therein for holding carbid, and means within the receptacle for producing free vapor directly in the vicinity of the

carbid whereby the vapor reacts on the latter to produce gas. 20

11. The combination of a chamber, means therein for holding carbid, means in the chamber for producing vapor in the presence of the carbid, means for supplying thermal energy from a point exterior of 25 the chamber to the vapor-producing means, and means for supplying water from a point exterior of the chamber to the vapor-producing means.

In testimony whereof I affix my signature 30 in presence of two witnesses.

ALEXANDER F. JENKINS.
